UNITED STATES PATENT OFFICE.

OTTO C. FOSSELMAN, OF MAYWOOD, ILLINOIS.

COUNTERBALANCED STAIR.

1,077,976.

Specification of Letters Patent. Patented Nov. 11, 1913.

Application filed February 16, 1912. Serial No. 678,093.

To all whom it may concern:

Be it known that I, OTTO C. FOSSELMAN, a citizen of the United States, residing at Maywood, in the county of Cook and State 5 of Illinois, have invented a certain new and useful Improvement in Counterbalanced Stairs, of which the following is a full, clear, concise, and exact description, reference being had to the accompanying drawings, 10 forming a part of this specification.

My invention relates to counterbalanced stairs such as are employed on the outside of buildings in association with fire-escapes, these stairs constituting the last flights to 15 the pavement. It is well known that counterbalanced stairs are employed for these purposes in order that it may not normally obstruct the streets or side passageways below and afford means for unauthorized access to the buildings. There is usually a 20 platform at the second floor of the building and installation of rigid stairways from this platform up to the top. The counterbalanced stair is mounted at this platform and 25 it lies normally in a horizontal position away from the ground. The stair is mounted upon a pivot and is counterbalanced by means of a weight. Because of the position of the platform and so as not to obstruct 30 the passageway leading to the counterbalanced stair, it is practical to place a counterbalancing weight on but one side of the stair and this is done by extending the outside stringer rearwardly beyond the pivot 35 rod. The inside stringer stops at the pivot rod. Then, because the outside stringer is counterweighted and the inside stringer is not counterweighted, there is a tendency for the forward end of the inside stringer to 40 sag, due to gravity, and this not only gives the fire-escape an unsightly appearance, but the distortion due to this sagging causes an infirm structure when the stair is swung down to touch the ground.

45 It is the object of my invention to provide means for overcoming this sagging effect, that is, for keeping the stringers in substantially parallel relation, and I do this by twisting the inside stringer before it is 50 bolted to the treads extending between the stringers. This causes an initial distortion at the front of the fire-escape and the twist is in such a direction that the inside forward end of the fire-escape will be distorted 55 upwardly and when the fire-escape is hung

the effect of gravity brings the stringers into parallel relation.

In order to assist the torsional effect in the inside or unweighted stringer, I provide an auxiliary torsion bar extending along the 60 side thereof, and bolted thereto in a manner to augment the twist, as will be described presently. I also provide novel weight means for securing the counterbalancing effect and I make these features the subject 65 matter of some of the appended claims.

My invention is illustrated in the accompanying drawings, in which—

Figure 1 is a plan view of the counterbalanced stair as it is hung upon the pivot 70 member; Fig. 2 is an end view illustrating the manner of twisting the uncounterweighted stringer; Fig. 3 is an end view showing the parts of Fig. 2 assembled; Fig. 4 is an elevational view of the stair before 75 it is hung upon the pivot; Fig. 5 is a view taken on the plane of the line 5—5 of Fig. 1 and looking in the direction indicated by the arrows; Fig. 6 is a sectional view taken on the plane of the line 6—6 of Fig. 4; and 80 Fig. 7 is a modified form of uncounterweighted stringer.

Like reference characters are applied to the same parts throughout the various figures.

Referring first to the general form of my fire-escape, it will be seen from Fig. 1 that the wall of a building is shown at 8 and that extending therefrom are brackets 9 which support a platform 10 and a pivot 90 rod 11. Mounted upon the pivot rod 11, by means of journal boxes 12 secured to the undersides thereof, are the inside stringer 13 and the outside stringer 14 which extend forwardly together, as shown, and have secured between them the plates 15, 15, preferably constructed of a plurality of rods set in end pieces 16, 16. Railings 17, 17 may be provided if desired. The outer stringer 14 is extended rearwardly beyond the pivot 100 rod 11 a considerable distance and it is there provided with a counter-weight 17 shown in detail in Figs. 1, 4 and 6. It will be seen that the stringer 14 is in the form of a channel beam and that the weight 17 105 is in the form of two halves together, one on each side of the stringer. Filler plates 18, 18 are provided and the bolts 19, 19 hold the parts together in properly assembled relation. The weight 17 is held in the plates 110

in any adjusted position by means of a set screw 20 and it will be seen that the weight can be adjusted longitudinally of the stringer. It is so disposed on the stringer 5 that when the stringer is in a horizontal position the preponderance of the weight will be at the rear; when, however, the stair is swung down, the center of gravity will be shifted, since the stringer is at a distance from the axis of the pivot member, so 10 that the preponderance of weight will be on the forward part of the stair. The set-screw 20 passes loosely through the parts of the weight, but is screw-threaded in a nut or plate 21 which is held stationary in a correspondingly shaped pocket in the weight, as shown in Fig. 4. It is evident that when the set-screw is tightened the entire weight will be firmly secured to the 15 stringer. In some cases it is necessary to provide an auxiliary weight 22 and I make this weight of such form that it may fit within the channel iron and provide it with lugs 23, 23 which fit in correspondingly shaped depressions 24, 24 on the inside of one of the weight parts. The forward end of this auxiliary weight is curved, as illustrated at 25, and it will appear that when it is desired to apply this auxiliary weight, 20 the set screw 20 may be loosened so that the main weight 17 may be drawn back, the auxiliary weight being then inserted in the main weight so that the lugs in the former will fit in the depressions in the latter and 25 the entire arrangement be then moved onto the stringer and secured in place. The curved or beveled forward edge of the auxiliary weight guides it properly into the channel iron. I provide this arrangement 30 so that the parts may be standardized and so that the weight 17 may always be employed, the auxiliary weight being used only when necessary, as in the case of a slightly longer stair.

40 As illustrated in Fig. 2, in the course of construction of the fire-escape, the plates 15, 15, by means of bolts 26, 26 passing through the end pieces 16 thereof, are secured to the channel iron forming the outside counter-weighted stringer 14. The uncounter-weighted stringer 13, however, is twisted in the direction of the arrow α so that in and of itself it will have the form 45 illustrated in Fig. 2 and in Fig. 1 in dotted lines. That is, the forward end of the stringer is twisted about ninety degrees from the rearward end and the stringer then has the tendency to always assume this shape. When the stringer 13 is turned back 50 in order that the free ends of the plates may be bolted thereto, this tendency is resisted. The supremacy of the torsion in the stringer 13, however, throws down the plates 15, 15 and the result is that the inside forward corner of the stair rises relatively as 55

70 illustrated in Fig. 3. When the stair is hung upon the pivot member, the stringer 14 is held in a definite position by the counter-weight and, but for gravity, the end of the inside counter-weighted stringer would rise. Since the inside stringer is uncounter-weighted, gravity acts to bring down the end of the inside stringer and, the twist originally being made to the proper extent, the stringers are then brought into substantially lateral alignment. In this way the sag is counter-acted and the stair may have the proper appearance and may also have the parts in proper mechanical arrangement. 75

80 It will be noted that in Figs. 1 to 5 the inside uncounter-weighted stringer is shown as a twisted plate. In order that a plate of this kind may be increased in the amount of tension stored therein, if necessary, I provide a rod 27 extending lengthwise thereof and secured thereto as follows: The ends of the rod are widened as illustrated at 28, 28, forming arms in both directions, and one arm at one end is provided with a lug or extension 29 which engages the face of the 85 plate. A bolt 30 passes through the opposite arm at that end and a bolt 31 passes through the diagonally opposite arm at the other end and when these bolts are tightened down the rod 27 will be twisted in a direction supplementing the twist of the stringer 13 itself. Quite the same result may be secured by using a channel iron 13^a, as illustrated in Fig. 7, in place of the flat stringer 13 since the edges of this iron add to its 90 stability and secondly, the amount of torsion which may be stored therein. 95

100 I claim as new and desire to secure by Letters Patent:

1. A stair comprising stringers hung upon a horizontal pivot rod, a counterweight applied to but one of said stringers, the other of said stringers being twisted about its own axis, a torsion rod secured and confined to said last-named stringer and treads 105 secured between said stringers. 110

2. A stair comprising stringers hung upon a horizontal pivot rod, a counterweight applied to but one of said stringers, the other of said stringers being twisted about its own axis, and treads secured between said stringers, the twist in the unweighted stringer tending to impel said counterweighted stringer downwardly. 115

3. A stair comprising stringers hung upon a horizontal pivot rod, one of said stringers having an extension rearwardly beyond the pivot rod, a counterweight on said extension, the other of said stringers being twisted about its own axis, a torsion rod secured 120 and confined to said last-named stringer and treads secured between said stringers, the twist in said unweighted stringer acting to maintain the stringers in substantial parallel 125 relation. 130

4. A stair comprising stringers hung upon a horizontal pivot rod, a counterweight applied to but one of said stringers, and treads secured between the stringers, the normal position of the weighted stringer with the treads attached being planar and the normal position of the unweighted stringer being twisted or warped.

5. The process of alining the stringers in 10 a counterbalanced stair in which but one stringer is counterweighted, which consists in twisting the unweighted stringer.

6. The process of alining the stringers in

a counterbalanced stair in which but one stringer is counterweighted, which consists 15 in securing the treads to the weighted stringer, twisting the unweighted stringer, and securing the treads to the twisted stringer.

In witness whereof, I hereunto subscribe 20 my name this 8th day of February, A. D., 1912.

OTTO C. FOSSELMAN.
